SHOE SHANK SUPPORT

Meyer D. Gilbert, New York, N. Y.

Application March 26, 1931. Serial No. 525,407

6 Claims. (Cl. 36—76)

This invention relates to accessories for shoes and is directed particularly to a device for supporting the arch of the foot.

An object of this invention is to provide a device of the character described having highly improved means for readily mounting the same on, and dismounting the same from, the underside of the shoe adjacent the heel.

A further object of this invention is to provide 10 a neat, compact and strong and durable device of the character described which shall be comparatively inexpensive to manufacture, simple in construction, easy to manipulate, substantially hidden from view in use, and withal practical and 15 efficient to a high degree.

Other objects of this invention will in part be obvious and in part hereinafter pointed out.

The invention accordingly consists in the features of construction, combinations of elements, 20 and arrangement of parts which will be exemplified in the construction hereinafter described, and of which the scope of application will be indicated in the following claims.

In the accompanying drawing, in which is 25 shown one of the various possible illustrative embodiments of this invention,

Fig. 1 is a bottom plan view of a shoe provided with an accessory embodying the invention;

Fig. 2 is a cross-sectional view taken on line 30 2—2 of Fig. 1;

Fig. 3 is a perspective view of the accessory shown in Figs. 1 and 2;

Fig. 4 is a view similar to Fig. 2 but showing a modified construction of the accessory; and

Fig. 5 is a cross-sectional view taken on line 35 5—5 of Fig. 4.

Referring in detail to the drawing, 10 designates a shoe, and 10a an accessory embodying the invention applied thereto. The shoe 10 comprises a heel 11, and a shank portion 12 adjacent thereto, the inner portion 13 of said shank being disposed beneath the arch of the foot. Said accessory 10a may be attached to the underside of the shank 12 and adjacent the front edge 40 14 of the heel in the manner hereinafter described in detail. Said accessory 10a comprises a body 15 made of soft rubber or the like moldable resilient or compressible material, and is provided with a bottom face 16 preferably flush with the 45 bottom surface of the heel, and with an upper surface 17 adapted to contact the undersurface 18 of the shank. The member 10a is further provided with a rear curved edge portion 19 adapted to contact the front curved edge portion 50 14 of the heel.

Said accessory 10a may be of substantially triangular shape, the curved apex portion 20 thereof being disposed closer to the portion 13 of the shank, so as to support the arch of the foot. It will be noted that the side edges 22 and 60 23 of said member 10a converge from the heel inwardly away from the side edges 24 and 25 of the shank whereby said member 10a is substantially hidden from view when in use.

Improved means is provided for attaching the 65 member 10a to the shoe. To this end there is embedded within the block 15, a horizontal tube or sleeve 30, and disposed within said sleeve adjacent one end thereof is a small coiled tension spring 31. Said sleeve serves to protect and house 70 the spring and permits stretching of the spring therein. Attached to one end of said spring is a bent wire member 32 having a portion 33 parallel to the surface 18 of the shank, and extending to the exterior of the body 15. Extending from said portion 33 is a portion 34 perpendicular to said shank and extending substantially into contact therewith. Extending from said portion 34 is a portion 35 adapted to lie against said shank, and terminating in a hooked portion 36 adapted to 75 grip the side edge portion 24 of the shank. Attached to the other end of the spring 31 is a member 37 substantially similar to said member 32 and likewise provided with a hooked portion 36a adapted to engage the edge portion 25 of the 80 said shank. The end of the tube adjacent spring 31 is preferably formed with an apertured end wall 31a for anchoring one end of the spring. It will be noted that in attaching the member 10a to the foot, one hook 36a may be first engaged 85 with the side edge 25 and the body 15 then pulled toward the opposite edge 24 to permit the hook 36 to engage said latter side edge. The body 15 may then be pushed toward the edge portion 14 of the heel against which it snugly fits to provide a firm 90 and strong attachment to the shoe.

In removing the member 10a from the foot, it is merely necessary to grasp the body 15 and move the same toward side edge 24 of the shoe to first disengage hook 36 and then move said body to the 100 opposite direction to disengage the other hook.

In Figs. 4 and 5 there is shown an accessory 50 of modified construction. Said accessory 50 comprises a block 51 made of two super-imposed soft rubber body portions 52 and 53. The upper portion 52 is provided with a recess 54 having a plurality of parallel end walls 55 and 56. Said block 52 is further provided with a pair of slits 57 and 58 parallel to said end walls 55 and 56 respectively. A pair of slits or undercuts 59 and 60 extending 110

from the top wall 61 of said cut out portion or recess 54 interconnect the recess with said slits 57 and 58 respectively, to form a pair of yieldable strips 62 and 63.

- 5 A pair of symmetrically disposed substantially similar members 65 and 66, made of bent and shaped wire are provided with hook portions 65a and 66a respectively, engaging said bands 62 and 63. The members 65 and 66 are further formed 10 with portions 69 and 70 respectively parallel to the lower surface 71 of the said block 52 and with portions 72 and 73 respectively contacting the outer side edges of said block. Extending from said portions 72, 73 are portions 74 and 75 15 contacting the upper surface of the shank and terminating in hooks 76 and 77 engaging the side edges of the shank. The block 53 may be attached to the block 52 after the wire members 65, 66 have been set in position. The block 52 may 20 further be provided with grooves 80 and 81 for receiving the portions 69 and 70 of said members 65 and 66. The accessory 50 may be attached or detached from the shoe in the same manner as the accessory 10a.
- 25 It will thus be seen that there is provided a device in which the several objects of this invention are achieved, and which is well adapted to meet the conditions of practical use.

As various possible embodiments might be made 30 of the above invention, and as various changes might be made in the embodiment above set forth, it is to be understood that all matter herein set forth or shown in the accompanying drawing, is to be interpreted as illustrative and not in a 35 limiting sense.

Having thus described my invention, I claim as new and desire to secure by Letters Patent:

1. A shoe accessory comprising a body made of 40 soft rubber and means for attaching the same to the underside of the shank of a shoe, said means comprising a pair of hook members and resilient means interposed between said members to permit said members to be pulled apart and said body having a cavity for housing said resilient means.

2. In combination with a shoe having a heel and a shank portion, a substantially triangular shaped arch supporting member, and means for attaching said member to the underside of the shank and adjacent said heel, said means comprising a pair of hook members adapted to engage opposite edges of the shank of said shoe, and a spring attached to said hook members and housed within said block. 80

3. In combination with a shoe having a heel and a shank portion, a substantially triangular shaped arch supporting member, and means for attaching said member to the underside of the shank and adjacent said heel, said means comprising a pair of hooked members and yieldable means interposed between said members and housed within said members to permit the same 90 to be pulled apart.

4. In combination with a block of soft rubber, means for attaching the same to the undersurface 95 of the shank of the shoe, said means comprising a pair of members, each member having a portion parallel to said surface of said shank and disposed within said block, a portion contacting said surface of said shank, a portion interconnecting 100 said first two portions, and a hooked portion extending from said second portion adapted to engage a side edge of said shank.

5. An accessory of the character described comprising a block of rubber having a pair of yieldable 105 strips and means for attaching said block to a shank of the shoe, said means comprising a pair of oppositely disposed members having means for engaging said strips and means for engaging the side edges of said shank. 110

6. A shoe shank support comprising a block, and means for attaching the same to the underside of a shank of a shoe, said means comprising a pair of hook members, a spring interconnecting 115 said members to permit said members to be pulled apart, and a tubular member within said block housing said spring.
